[57] **CLAIM**

The ornamental design for a pruner, as shown and described.

DESCRIPTION

FIG. 1 is a side perspective of the pruner showing my new design;
FIG. 2 is a top plan view thereof;
FIG. 3 is a right side elevational view thereof;
FIG. 4 is a bottom plan view;
FIG. 5 is a left side elevational view thereof;
FIG. 6 is a front elevational view thereof;
FIG. 7 is a rear elevational view thereof;
FIG. 8 is a perspective view of second embodiment of the design shown in FIG. 1;
FIG. 9 is a right side elevational view thereof;
FIG. 10 is the left side elevational view thereof;
FIG. 11 is the top plan view thereof;
FIG. 12 is the bottom plan view thereof;
FIG. 13 is the front elevational view thereof;
FIG. 14 is the rear elevational view thereof;
FIG. 15 is a perspective view of a third embodiment of the new design shown in FIG. 1;
FIG. 16 is a top plan view thereof;
FIG. 17 is a right side elevation view thereof;
FIG. 18 is a bottom plan view thereof;
FIG. 19 is a left side elevational view thereof;
FIG. 20 is a front elevational view thereof; and
FIG. 21 is a rear elevational view thereof.
